TOOL FOR OBTAINING LINING OR PACKING
FOR A BRASSIERE

Maurice Rousseau, 41 Rue de La Tranchée,
Poitiers, France

Original application Aug. 28, 1957, Ser. No. 680,792, now
Patent No. 3,041,903, dated July 3, 1962. Divided
and this application Jan. 6, 1960, Ser. No. 818

3 Claims. (Cl. 82—12)

The present invention relates to a means and method for forming linings or packing for brassieres and is a division of application Serial No. 680,792, filed August 28, 1957, now Patent No. 3,041,903 issued July 3, 1962.

This invention relates to an improved tool for making lining or packing for a brassiere.

An object of the invention is to provide a tool for cutting out brassiere paddings or linings in a single piece on a lathe with the piece having several easily detachable layers. One or more layers may be removed at will so that the brassiere cup may be properly filled.

Another object of the invention is to provide a tool for cutting out small dimensioned packing on a lathe useful as false breast nipples for a woman whose bust does not fill up the point of a brassiere.

Another object of the invention is to provide a tool for obtaining the afore-mentioned linings or packings by means of a lathe, in a simple and practical manner.

The invention also applies to the characteristics herein-after mentioned and to their various possible combinations.

A device according to the invention is shown by way of non-restrictive example in the attached drawings, in which:

FIGURE 1 is a longitudinal sectional view illustrating a method for cutting out a lining or packing.

FIGURE 2 is a longitudinal view showing a method for cutting out of a hollow lining or packing.

FIGURE 3 is a longitudinal sectional view showing a method for cutting out linings for use as false breast tips from the cuttings left overs.

FIGURE 4 is a longitudinal sectional view showing the successive cuts of parallel-faced linings or packings.

FIGURE 4 bis is a longitudinal sectional view showing a lining with several layers.

FIGURE 5 is a view showing the extreme curvature shapes that can be given to the surface of revolution.

FIGURE 6 is a longitudinal sectional view showing the cutting of a spherical tip at the apex of the false breast.

FIGURE 7 is a longitudinal sectional view showing a padding with a nipple.

FIGURE 8 is a view illustrating the cutting of non-parallel-faced linings.

FIGURES 9 and 10 are front and top views of the tool with which linings are made.

FIGURE 11 is a view of the end of the tool.

FIGURE 12 is a view of the tool set in the case where the mass of material is rotatively mobile.

FIGURE 13 is illustrative of a preferred form of the invention wherein the tool is rotatively mobile.

FIGURES 14 and 15 are front and top views of alternative cutting tools.

The lining or packing shown in FIGURE 1 is a solid cup suitable, for example, for a person who has undergone an operation; this cup is obtained by cutting out a mass of cylindrical flexible material 1 such as polyurethane foam along a first surface of revolution with a circular arc profile 2 centered at A₁.

Then, a second surface of revolution with a circular arc profile 3 centered at B₁ is cut.

Thus, two surfaces of revolution are obtained, one concave 2, the other convex 3 forming between them the cup

2

which forms the padding. The surface 2 is intended to rest against the chest, the surface 3 forming the external shape of the artificial breast.

The surfaces of revolution are obtained by introducing a thin tool into the material, this tool being tapered and with a cutting edge at its end: are rotated relative to each other: the point of the tool penetrates only as far as the cylinder axis at the point S along the trajectory LS. It is the rotational movement which effects the complete cutting out along SL' symmetrical with SL in relation to the rotation axis of the cylinder 1 of flexible material.

The center B₁ of the surface 3 is offset in relation to the axis of the cylinder, which enables a profile of two intersecting circular arcs to be imparted to the external surface of the lining.

In the case of FIGURE 2, a hollow lining 5 is obtained intended to contain an under-developed breast, this lining being achieved by effecting in the cylinder:

(a) The cutting of a surface of revolution 2 similar to that of FIGURE 1;

(b) The cutting out of a surface of revolution 4 by a method similar to the cutting of the surface 3 but of a smaller dimension than surface 3; and

(c) The cutting of the surface of revolution 3.

In the case where a lining is desired to be obtained, as in FIGURE 2, cuttings 6, will be found to left over.

These cuttings 6 may be advantageously used for making breast "tips" (or reduced sized cups, utilised for women who do not entirely fill out the tip of their brassiere).

To make the latter (FIGURE 3), it is only necessary to precede the center cut B₂ by successive cuts with respective centers B₅, B₄, B₃. The cups 7₄, 7₃, 7₂, 7₁, are thus obtained.

In other words, the rational method of cutting out cups and additional breast tips is as follows:

(a) plotting the center axis A₁;

(b) plotting in their order, arcs 4₁, 4₂, 4₃, 4₄ of centers B₅, B₄, B₃, B₂, (this latter arc terminating the series of breast tips and preparing the internal face of the lining itself);

(c) plotting the arc 3 of the center B₁ which determines the normal lining 5.

When parallel-faced linings are required as illustrated in FIGURE 4, a first cup 5 is cut out, of which the cut-out external face 3 will form the cut-out internal face of the following cup 5₁. As soon as the cup 5 is detached, a circular arc Z₁ is plotted from A₂ intended to cut out the base of the cup and allowing the cutting 8 to fall.

Then, from B₆ the external face 3 is cut out, this cut also determines the cut of the interior face of the following cup.

This operation is mentioned in the same manner; centered circular arc A₃ then centered circular arc B₇, centered circular arc A₄ then centered circular arc A₄, and so on.

The curvature of the various surfaces of revolution is adjustable as illustrated in FIGURE 5, depending on the curvature of the tool and the pivoting center of this tool.

In this manner it is possible, by means of a rectilinear tool, to obtain tapered linings 10, the pivoting center being very distant, or else, in the other extreme case, a crescent 11, the tool having a semi-circular profile and the pivoting center being at the actual border of the cylinder.

It is not indispensable to utilise the same compass opening, on the one hand for the centers A (base arc of the breast) and on the other hand, for the centers B (curvature arc of the breast), FIGURE 5 being an example of this. But certain advantages are afforded by retaining the same opening, both for plotting as well as

70

machining, since in this latter case, a single tool for cutting serves for both arcs.

The angle formed between these two arcs at their intersection has a great advantage when the cup is intended to be sewn into a brassiere. If this angle is acute (as in FIGURES 1 and 2) it permits the brassiere manufacturer to sew the periphery of the lining between two seams, around the inner lining of his brassiere.

There may be some advantage in the two faces of the lining not being parallel as illustrated in FIGURE 8.

Certain brassiere makers prefer a cup model that is thicker in the center than at the edges (more flexible edges) 14.

Others prefer the edges to be thicker (better fit and more flexible point) 15.

One or other of these models can be easily obtained (or both alternately, since they complement each other) as shown in FIGURE 8, by cutting the internal faces of the thin-edged linings or packings 14 (hence, the external faces of the thick-edged cups 13) from the centers B_{10} , B_{11} , B_{12} , and the external faces of the thin-edged lining 14 (hence, the internal faces of the thick-edged lining 13) from the centers C_{10} , C_{11} , C_{12} .

By stopping the knife as it goes into the foam, before the end of its trajectory, a cup is obtained that is still attached to the following one by its central part as illustrated in FIGURE 4 bis.

By successively thrusting the knife into the rotating foam, at various depths, along the cutting lines 3_A , 3_B , 3_C , an artificial breast is obtained in a single piece, but composed of a varied number of cups, i.e., an artificial breast made up of several layers 3_A , 3_B , 3_C , 3_D (FIGURE 4 bis).

Rounded-Tip Linings and Linings Provided With a Nipple

The flexibility of polyurethane foam has been mentioned above. It is such that in densities of 35 to 50 kgs./m.³ it affords two alternatives that can be applied to all the aforementioned models.

1st Alternative—Rounded-Tip Linings (FIGURE 6)

When the shears have completed about $\frac{3}{4}$ of their trajectory inside the foam, it is possible, owing to this flexibility to impart to the cutting end of the knife, a recoil movement concomitant with the terminating by the knife of the last one-fourth of its trajectory.

This causes the knife to rub on the cup during the finishing stage and has the effect of giving the lining a more rounded tip (as a matter of fact, certain brassieres have this profile) (FIGURE 6).

2nd Alternative—Linings Provided With a Nipple

When the shears have arrived at about $\frac{1}{10}$ of their normal trajectory inside the foam, it is possible, owing to the flexibility of the latter, to impart to the cutting end of the knife, a forward movement concomitant with the terminating of $\frac{1}{10}$ of this trajectory.

This causes the knife to rub on the block of raw material and give to the artificial breast, during the finishing stage, a tip which perfectly imitates the natural nipple of the breast. All shapes of tips can be secured by synchronizing at will the forward movement of the knife point with the forward movement of the carrier system.

For a knife about 8 mm. wide, the flexibility of the polyurethane foam enables forward movements of 8 to 10 mm. to be made, which is more than sufficient for obtaining a breast tip that simulates the natural nipple (FIGURE 7).

Subsequent Cuts

The machined artificial breasts and cups, when seen from the front, have a circular aspect and are often used in this state.

Subsequent cuts will impart all possible shapes to them, and more particularly:

(1) By cutting them out to the exact shape of a brassiere cup of a given type.

(2) By cutting out their upper one-fourth for adapting them to a brassiere known as a "basket" or "balloon."

(3) By cutting them out in the middle to obtain what is called a "semi-breast" intended to be placed in the bottom of any kind of brassiere cup and thus increasing the apparent size of the bust to the same extent.

In these three cut-out shapes, it would be advisable to recut the edges of the linings so that the latter are very tapered and that the stiffening that they form fits naturally and snugly on the user's breast.

15

Tool Equipment

The knife or tool 13 (FIGURES 9, 10, 11) may be made of a chilled forged steel blade, of variable width and reduced thickness, curved exactly according to the radius R of the cup that is required.

20

This blade is sharpened at the end only.

For machining flexible materials, such as polyurethane foam, a thin blade with a tapered cutting edge, parallel to the cutting line is used. The flexibility of the material enables the shears to sink into the circular slot that its point makes in the material (FIGURES 9 and 10).

Two Cutting-Out Methods

For greater clearness, it is sufficient to describe these two methods in their most rudimentary form, it being obvious that all automatic or semi-automatic fittings based on the same principles and utilising the same methods are possible.

(a) *First method (FIGURE 13).*—The tool head turns and the work piece is stationary.

The blade 15 is curved along an arc of radius R and extends over a little less than a semi-circumference of center o. This blade penetrates the work-piece 1 advancing in the direction of arrow f.

40

It slides, with no play, in a slot 16 of the like semi-circular shape and is retained at its non-cutting end by a spring 17.

This semi-circular slot is welded at its middle to a hollow shaft 18 and this latter is fixed on a holder carriage 24. This holder carriage is articulated so that the center o of the knife may successively take the positions of the various centers of cutting A and B. (FIGURES 1, 2, 3, 4, 4 bis).

The sliding blade may obviously be drawn in or out of its slot at will by means of a simple handle and cable 25 inside the shaft.

It may easily be understood that the penetration of the cutting edge of the blade 15 in the work piece 1 results in cutting the material of the work-piece along an arc R of center o. Because of the rotary motion about the axis x, y of the holder shaft 18, the blade cuts the work-piece along a surface of revolution.

The tool may be adjusted thereafter to cut lining of various forms such as those which have been described above.

60

(b) *Second cutting-out method (FIGURE 12).*—The raw material, and not the tool holder, turns. The blade is welded to a movable tool-holder plate 19 which the operator holds by two handles 20 and 21.

A steel point or projection 22, perpendicular to the major plane of the tool-holder, is welded to the tool-holder and acts as pivoting axis for the tool-holder.

A horizontal platform holder carriage 23 moves parallel to the axis of the cylindrical mass 1 and has rows of holes A—B—C in the platform for receiving the above-mentioned steel point.

These holes are drilled in positions to locate cutting-out centers for the various surfaces.

By a revolving movement of the tool-holder around this projection 22, the blade may be thrust into the rotat-

75

ing foam. The cylindrical mass or workpiece 1 is supported on suitable means 39 for rotating the workpiece. This means 39 may be driven by a suitable drive means 31. Elements 30 and 31 may be formed as part of a lathe or the like.

The invention is not restricted to the forms of embodiment precisely described and shown, and from which other alternatives may be provided without departing from the scope of the invention.

What I claim is:

1. Tooling for the manufacture of an article having multiple curved surfaces of revolution, comprising means to support a work-piece of flexible and spongy material to be cut, a cutting tool with a cutting edge having a curvature corresponding to that of the surfaces of revolution to be obtained and able to be given a curvilinear motion of penetration around its center of curvature, a tool head pivoting in a diametral plane of the cylindrical work-piece and the pivot of which is made of a center point, a supporting plate for said tool head, said supporting plate having several holes for said center point of the tool head located at the points of the successive centers of rotation of said tool head.

2. Tooling for the manufacture of an article having multiple curved surfaces of revolution comprising means to support a work-piece of flexible and spongy material to be cut, a cutting tool with a cutting edge having a curvature corresponding to that of the surface of revolution to be obtained and able to be given a curvilinear motion of penetration around its center of curvature, a tool head pivoting in a diametral plane of the work-piece and the pivot of which is made of a center point, a supporting plate for said tool head, said supporting plate having

10

15

20

25

30

several series of holes for said center point of the tool head, the holes of each series being located in rows, at the points of the successive centers of the tool-head.

3. Tooling for the manufacture of an article having a plurality of curved surfaces with equal diameters comprising,

means for supporting a workpiece of flexible, spongy material to be formed into said article,
a cutting tool having a sharp edge shaped to correspond to said surfaces, means to rotate said tool by imparting to it a curvilinear motion around its center of curvature,
a tool holder for supporting said tool as it cuts said workpiece, said tool holder being pivotably mounted on a projection for pivotal movement in a plane which is diametric to the workpiece,
a supporting base for pivotably supporting said tool holder in a plurality of aligned positions parallel to an axis of rotation of said workpiece for penetrating said tool in said workpiece,
said supporting base containing a plurality of openings arranged in a plurality of linear series, with each linear series being parallel to the workpiece, whereby any of said openings may be engaged with said projection and the center of pivotal support of the tool holder changed, and
means for rotating the workpiece.
